Primary Examiner — Elizabeth J Oswecki(74) *Attorney, Agent, or Firm* — Allen, Dyer, Doppelt, Milbrath & Gilchrist, P.A.(57) **CLAIM**

The ornamental design for a Christmas tree, as shown and described.

DESCRIPTION

FIG. 1 is a left perspective view of a Christmas tree showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is left perspective view thereof shown in a used condition; and,

FIG. 9 is a right perspective view thereof shown in a used condition.

In the drawings, the broken lines in FIGS. 8 and 9 depict portions of the design that form no part of the claim.
